UNITED STATES PATENT OFFICE.

JOHN W. SCHWOERER, OF CINCINNATI, OHIO.

PORTABLE WASHING AND RINSING MACHINE.

1,054,990.

Specification of Letters Patent.

Patented Mar. 4, 1913.

Application filed December 26, 1911. Serial No. 667,866.

To all whom it may concern:

Be it known that I, JOHN W. SCHWOERER, a citizen of the United States, residing at Cincinnati, in the county of Hamilton and 5 State of Ohio, have invented certain new and useful Improvements in Portable Washing and Rinsing Machines, of which the following is a specification.

My invention relates to portable hand or 10 power operated washing and rinsing machines.

The object of my invention is to provide a convenient, efficient and highly sanitary portable washing and rinsing machine for 15 the purpose of washing and rinsing diapers and also badly soiled garments in running water in a closed receptacle which can be readily attached to the edge of a wash tray, bath tub, wash tub and the like, and conveniently secured to the ordinary water 20 service and drains respectively.

Another object of my invention is to provide a closed washing and rinsing machine which is practically odor-proof and which 25 eliminates the necessity of the operator handling the clothing after it has been placed therein during the operation of washing and rinsing.

Another object of my invention is to provide 30 a suitable receptacle for soiled garments as fast as they accumulate and thus avoid the necessity of again handling them until they are washed and rinsed.

Thus it is seen that my invention is 35 adapted for the purpose of washing diapers and badly soiled garments after being used by infected persons, without danger, thereby insuring freedom from disagreeable odors and infections emanating from the same.

40 In the accompanying drawings, which serve to illustrate the construction, application and use of my invention: Figure 1 is a vertical section of the device clamped to the side of a stationary tub, the water inlet 45 being connected to an ordinary water faucet by means of a flexible tube; Fig. 2 is a plan view of the same; Fig. 3 is a side elevation looking at right angles to the view shown in Fig. 1; Fig. 4 is a side elevation of the 50 device on a somewhat smaller scale, showing the device clamped to the side of a bath tub; and Fig. 5 is a detail perspective view of a saddle used in clamping the machine to a bath tub.

55 In the embodiment of my invention, as

illustrated, and which shows my preferred construction, 1 represents the cylindrical receptacle or tank and 2 the lid which is suitably hinged thereto at one side and provided with a handle 2' on its opposite side 60 by which the lid may be moved upon its hinges. A water inlet opening 3 is provided preferably near the top of the tank and a fluid outlet opening 4 at the bottom thereof. Slightly below the water inlet opening 3 I 65 provide an overflow outlet 5 which connects through pipe 6 to a drain pipe 7 on the outside of the receptacle. This overflow serves as a gage to insure the maintenance of the proper amount of water within the receptacle 70 at all times and serves as an overflow to permit a constant flow of water through the machine during the operation of washing to carry off the suspended particles of matter which have been freed from the clothing 75 during the washing and rinsing operation. The drain pipe 7 is preferably provided with a valve 8 placed between the receptacle and the overflow pipe and having a passage therethrough equal in size to the diameter of 80 said drain pipe to permit the free discharge of any sediment which may accumulate and also the quick discharge of the fluid contents of the receptacle when desired.

The location of the valve 8 in the outlet 4 85 upon the outside between the vessel 1 and the pipe 6 permits the discharge or overflow of water from the vessel either through said pipe 6 alone or in conjunction with the outlet 4 and in the latter case the vessel can be 90 entirely drained and thoroughly cleaned conveniently and very quickly. Being on the outside of the vessel it also enables me to easily and conveniently operate the valve at any time during the operation of washing 95 while the machine is filled with water and clothing and to enable me to adjust the valve to any position desired for the purpose of causing the desired amount of discharge through said outlet 4, a greater discharge 100 being desirable when there is considerable sediment removed from the clothing when first placed in the machine and as the operation of washing or rinsing continues the discharge at the lower part of the vessel should 105 be lessened and the discharge at the upper part increased for the reason that the lighter particles of sediment dislodged from the clothing will be sufficiently light to rise to the surface of the water and be discharged

through the outlet 5. This effects a saving in the use of water as well as soap as there is a more gradual change in the water and the soapy water can be used for a longer period than when it is being discharged at the bottom as well as at the top.

An agitator 9 is provided and is mounted upon a shaft 10, which shaft 10 is slidably mounted in a bearing 11 in the lid 2 of the machine. Said shaft 10 is also slidably mounted within pinion 12 which is provided with a spline 13 which fits in a suitable spline-way on the shaft 10 and allows said shaft 10 to slide longitudinally relatively 15 to said pinion but causing it to turn therewith. The shaft 10 is also supported in a bearing 14 which is supported by means of an upwardly extending bracket 15 which is suitably fastened to the plate 16 mounted 20 upon the lid 2. The upper end of shaft 10 is provided with a handle 17 which may be used to raise and lower the agitator 9 for the purpose of opening the lid upon its hinge or pivot 18. In order to open the lid 25 it is necessary to raise the agitator to its uppermost position and when it has been thus raised it may be held in its raised position relatively to the lid by means of tightening the thumb screw 19 mounted in 30 a collar 20 on the shaft 10. However, as soon as the lid is closed the thumb screw must be loosened before the agitator is lowered for vertical play inside of the tank in the operation of washing. This is desirable 35 in order to permit the dasher to adapt itself to varying quantities of clothing within the tank and to permit of vertical as well as rotary reciprocating motion at the same time to obtain a more thorough and complete agitation of the clothing during the operation 40 of washing and rinsing.

The plate 16 mounted on the lid 2 is provided with a boss 21 near the edge of the lid 2 and has pivoted thereto at 22 a gear segment 23. Said gear segment is provided with an extension 24 to which a handle 25 is secured. When the handle 25 is oscillated upon its pivot 22 the gear segment 23, meshing with the pinion 12, oscillates said pinion 50 and thereby oscillates the agitator 9 giving it a reversible rotary movement through the agency of shaft 10.

In order to provide an efficient clamp for securing said device to the side of a stationary tub or the like, I secure two angle irons 26 to one side of the receptacle and to these angle irons I fasten two vertical wooden bars or strips 27. These bars or strips form a bearing surface for the side 55 of the device and prevent the same from marring any object to which it is attached when clamped in position for use. Pivoted between said bars and at a point below the lid 2 of the machine is a goose-neck bracket 60 28 carrying at the outer end thereof a thumb

screw 29. Said thumb screw is passed through the outer end of said goose-neck bracket 28 and carries a bearing plate 30 at the end thereof which is adapted to bear against the edge of the tub or other object. 70 The center line of the thumb screw is preferably on a line with the pivotal point of the goose-neck bracket 28, thus producing the most efficient connecting or clamping means for said washing and rinsing machine. 75

To fasten the device to a bath tub, I provide an angular shaped central member 31 which has a concave recess 32 in its bottom which is adapted to rest upon the rolled edge 33 of bath tub 34 as shown in Fig. 4. The vertical side of the angular shaped bracket 31 then takes the place of the side of the stationary tub shown in Fig. 1, the machine being clamped in precisely the same 85 manner to said vertical portion of the bracket 31. The bracket 31 is reinforced with a metal bracket 36 as shown in Fig. 5. The lower extension 37 of said bracket 36 extends under the roll portion 33 of the bath 90 tub and is provided with a thumb screw 38 which has a bearing plate 39 at the end thereof adapted to bear against the under side of a roll rim 33 of the bath tub, thus 95 clamping the angular shaped bracket 31 to the bath tub rim and consequently clamping the entire washing machine to said bath tub.

The operation of the device is as follows: The machine is properly clamped in position 100 upon a stationary tub or bath tub as above described and the inlet tube or hose 40 is connected to the hot or cold water faucet 41 as desired. The valve 8 is closed and the drain 7 is connected to the sewer by means 105 of flexible tube 42 having a tapering adjustable coupling 43 on the end thereof adapted to fit varying sizes of outlets. The water is then turned on and the clothes agitated by means of the agitator 9 which is operated by the handle 25 or by means of other suitable power. The operation of the agitator in the running water which is always maintained at the proper height by means of the overflow gage outlet 5 will reduce all solid 110 matter into solution and suspension in the water which is automatically discharged through the overflow outlet or opening 5 thus constantly carrying off the soiled matter as rapidly as it is released from the 115 clothing by means of the agitation and carrying it through the drain connection 7 and tube 42 into the sewer connection, thus forming a thoroughly practical and efficient sanitary washer and rinser. 120

One of the chief advantages of my invention is that it acts as a receptacle to hold soiled garments which may be immediately immersed in the water and allowed to soak until ready to wash or each garment may 130

be agitated separately upon being placed in the receptacle and then allowed to soak, until sufficient clothing has accumulated for a washing. The matter can be driven into the sewer immediately after depositing each garment by means of the running water inasmuch as it rinses them, washes them and then rinses them again, thus cleansing the garments without it being necessary to touch a single one with the hands. The device can be readily attached to wash tubs or bath tubs, and to the ordinary and usual inlet water connections and sewer connections by means of rubber hose which may be easily connected by hand, only a slight pressure being required to connect them. These features make it absolutely safe for the operator to wash soiled germ laden garments without any fear of contagion or without fear of inhaling any deadly germs or fumes which are prevented from escaping from the closed receptacle.

It will be noted that this washing and rinsing machine is for purposes other than those which can be accomplished by the ordinary washing machine. In addition to the advantages already enumerated, the hands do not touch the water or the garments during the whole operation and all water is drained from the cylinder or receptacle by gravity or natural drainage. A few strokes of the agitator will drive all surplus water from the garments leaving them merely damp.

My invention is capable of some modification without departure from the spirit or scope thereof.

I claim:

1. A portable washing and rinsing machine comprising a receptacle, adjustable means for supporting and holding said receptacle suspended within a stationary tub, a water inlet for said receptacle, a drain outlet at the bottom of said receptacle, an overflow near the top of said receptacle extending on the outside of same and discharging into said drain outlet and a valve in said drain outlet between said receptacle and said overflow, substantially as set forth and for the purposes specified. 50

2. A portable washing and rinsing machine comprising a receptacle, adjustable means for supporting and holding said receptacle to one edge of a stationary wash tub, and means for supplying a constant flow 55 of water to and from said machine during the operation of washing and rinsing, substantially as set forth and for the purposes specified.

3. A portable washing and rinsing machine comprising a receptacle, means for supporting and holding said receptacle, flexible means for connecting said receptacle to a water service, an overflow from said receptacle adapted to discharge said water and cause a constant flow of same therethrough and through a flexible sealed connection from said overflow with the sewer pipe, for the purposes set forth substantially as specified. 60 65
